CLAIM

The ornamental design for a gas combustor, as shown and described.

DESCRIPTION

FIG. 1 is a perspective view of a gas combustor showing the design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings depict unclaimed environmental subject matter.

1 Claim, 5 Drawing Sheets
